UNITED STATES PATENT OFFICE.

FRANK PLIMLEY YEOMANS, OF OAKLAND, CALIFORNIA.

NOISELESS RAILROAD CROSSING.

1,407,778.

Specification of Letters Patent. Patented Feb. 28, 1922.

Application filed October 29, 1921. Serial No. 511,306.

To all whom it may concern:

Be it known that I, FRANK PLIMLEY YEOMANS, a citizen of the United States, residing at Oakland, in the county of Alameda and State of California, have invented certain new and useful Improvements in Noiseless Railroad Crossings, of which the following is a specification.

This invention relates to improvements in railroad crossings, and more particularly to that type of crossing known as a continuous rail crossing or noiseless crossing.

An object of the invention is to provide a suitable railroad crossing which will entirely eliminate the noise that is customarily heard in the usual type of crossings.

Another object of the invention is to provide a railroad crossing which will not only be noiseless, but will also be so constructed as to make a derailment impossible.

A further object is to provide a railroad crossing which will be noiseless, and will also be automatic in operation, being operated by the trains as they come from either direction.

A still further object is to provide a suitable noiseless railroad crossing, which will be efficient in operation and inexpensive to manufacture.

Other objects will appear as the description proceeds.

In the accompanying drawings which form a part of my application:

Figure 1 is a plan view of my improved noiseless railroad crossing with the L-shaped inner rails.

Figure 2 is a sectional view taken on the line 2—2 of Figure 1.

Figure 3 is a detail view of the slotted guard rails which are positioned between the main crossing rails.

Figure 4 is a plan view of the crossing with straight inner rails instead of L-shaped rails, and

Figure 5 is a sectional view taken on the line 5—5 of Fig. 4.

Like characters of reference are used throughout the several views to designate corresponding parts.

The main rails 1 of the crossing are preferably formed in L-shape, having their adjacent ends welded together, or formed integrally when molded, although they may be composed of separate rails.

The main rails 1 are fastened to the ties

2, and have a portion of the inner bottom flange of the rails cut away as at 3. Positioned at either side of the main rails 1, are the L-shaped inner rails 4, in Fig. 1 or straight rails in Fig. 4, whose adjacent ends 5 are cut off diagonally, to permit of lateral movement.

The main rails 1 and rails 4, are separated by the guard rails 6, which are notched as at 7, as best shown in Figure 3. These guard rails 6 are placed in pairs, and the rail next to the main rails 1 is of considerably lighter stock or material than the guard rail adjacent the inner rails.

Extending through the webs of each of the main rails 1, are the slots 8, likewise through the guard rails and inner rails, the several slots being in alinement to permit the bolts 9 to pass therethrough. These bolts 9 are fixed to the web portion of the inner rails 4, and are adapted to receive the tensioning springs 10 over their free ends, which are held in proper position or adjustment, by means of the nuts 11. The outer ends of the guard rails 6 are bent outward as at 12, adjacent the cut away portion 3 in the main rails 1, so that the flanges 13 of the car wheels 16, will more readily separate the said guard rails, and run or pass there between.

The mode of operation of my improved noiseless crossing is as follows: Assuming that the several parts are in their proper positions, that is, the main rails 1 are fixed to the ties, and the inner rails and guard rails are held adjacent said main rails, by means of the bolts 9 and springs 10. The flange of the wheels will first strike the outwardly flared ends 12 of the rails 6, which causes the guard rails to spread or separate, thereby permitting the flanges of the wheels to ride in between the said guard rails. The inner rails will be forced towards each other, due to the overlapping of their adjacent portions, against the tension of the springs 10 on the bolts 9. The flanges of the wheels will pass through the slots 7 in the guard rails, whether the train is on either track, and the bases of the wheels will ride on the main rails 1 and the adjacent guard rail. As soon as the train passes over the crossing, the flanges of the wheels will ride out from between the guard rails, and the tension of the springs 10, will cause the several parts to return to their original position. In as

much as there are continuous rails at the crossings, and there are no gaps to bridge, there will be absolutely no chance or danger of a train becoming derailed.

- 5 In practically all railroad crossings in use today, the corners of the rails are soon worn off, and the crossings have to be replaced or repaired, whereas in my improved crossing, there is always a continuous rail 10 for each wheel, consequently eliminating the wear until it is at its minimum.

Whatever dirt may get in between the rails will drop down into a collecting pan or basin, to be disposed of in any desired manner.

- 15 The usual type of crossing plates will be placed in position, and may readily be removed for getting to the springs to adjust the tension, as cars of different weights 20 would require a difference of spring adjustment.

Many minor changes in detail of construction may be resorted to without departure from the spirit of the invention.

- 25 Having thus described my invention what I claim as new and desire to secure by Letters Patent of the United States is:

1. A noiseless railroad crossing comprising a plurality of L-shaped inner rails interposed between said main rails, a plurality of notched guard rails between said main and inner rails, and resilient means for holding the several parts in operative position.

30 2. A noiseless railroad crossing comprising a plurality of L-shaped main track rails, a plurality of L-shaped inner rails interposed between said main rails, a plurality of notched guard rails between said main and inner rails, all of said rails being provided 35 with registering slots, bolts passing through said slots, and means carried by said bolts for adjusting the tension between the several parts.

3. A noiseless railroad crossing comprising a plurality of L-shaped main track rails,

L-shaped rails interposed therebetween, a plurality of guard rails, resilient means for holding the several parts in operative position, means for adjusting the tension of said resilient means, and means for guiding a 50 wheel flange in between said guard rails.

4. A continuous railroad crossing comprising continuous L-shaped main rails in fixed position, inner rails adjacent said main rails, guard rails disposed between said main 55 and inner rails, and resilient means for holding the same in operative position.

5. A continuous and noiseless railroad crossing comprising a plurality of continuous L-shaped main rails, inner rails interposed therebetween, notched guard rails adjacent said main rails, flared ends on alternative guard rails, and adjustable resilient means for holding the several parts in operative position.

6. A continuous and noiseless railroad crossing comprising a plurality of L-shaped main rails, laterally adjustable inner rails, laterally adjustable guard rails interposed between said main and inner rails, all of said 70 rails being provided with alined notches, means extending through said notches for holding the same in position, and resilient means carried by said last mentioned means for tensioning the parts as desired.

7. A continuous and noiseless railroad crossing comprising angular main rails, means for holding said rails in fixed position, interposed inner rail sections, a guard rail or rails interposed between said main 80 and inner rails, means for causing lateral movement of one of said guard rails and the inner rail when a wheel flange passes on the crossing, and resilient means for retracting the several parts into their original position 85 when the wheel is off the crossing, substantially as described.

In testimony whereof I affix my signature.

FRANK PLIMLEY YEOMANS.
